DOll

Pearl I. Wheeler, Los Angeles, Calif.

Application February 19, 1949, Serial No. 958

Term of patent 7 years

(Cl. D34—4)

To all whom it may concern:

Be it known that I, Pearl I. Wheeler, a citizen of the United States, residing at Los Angeles, in the county of Los Angeles and State of California, have invented a new, original, and ornamental Design for Doll, of which the following is a specification, reference being had to the accompanying drawing, forming part thereof.

Fig. 1 is a front view of a doll in erect position embodying my new design;

Fig. 2 is a rear view of the same in erect position;

Fig. 3 is a side view of the same in erect position; and

Fig. 4 is a perspective view of the doll in a sitting position.

I claim:

The ornamental design for a doll, as shown.
PEARL I. WHEELER.
